UNITED STATES PATENT OFFICE.

ARTHUR M. GORDON, OF PLYMOUTH, CONNECTICUT, ASSIGNOR TO SETH THOMAS CLOCK CO., OF THOMASTON, CONNECTICUT, A CORPORATION.

TOWER-CLOCK ESCAPEMENT.

1,109,581.

Specification of Letters Patent.

Patented Sept. 1, 1914.

Application filed May 25, 1914. Serial No. 840,770.

To all whom it may concern:

Be it known that I, ARTHUR M. GORDON, a citizen of the United States, residing at Plymouth, in the county of Litchfield and State of Connecticut, have invented a new and useful Improvement in Tower-Clock Escapements; and I do hereby declare the following, when taken in connection with the accompanying drawings and the characters of reference marked thereon, to be a full, clear, and exact description of the same, and which said drawings constitute part of this application, and represent, in—

Fig. 1 a view in elevation of a tower-clock escapement constructed in accordance with my invention, showing the pendulum-rod partly broken away and swung to the extreme limit of its excursion to the right. Fig. 2 a corresponding view with the pendulum-rod in its intermediate position. Fig. 3 a view in elevation of one of the modified forms which my invention may assume. Fig. 4 a view thereof in transverse section, looking downward.

My invention relates to an improvement in that class of tower-clock escapements in which two pivotal gravity-arms are alternately lifted by the action of the power-train and their gravity action utilized to maintain the motion of the pendulum-rod which in turn raises the arms for releasing the escapement-wheel which transmits the power of the train to the arms in initially lifting them. Escapements of the type described have been found objectionable for the reason that they have not sufficiently taken into account certain factors, (such, for instance, as wind-pressure upon the hands) causing such a sudden excess of power as to lift the gravity arms with enough momentum to carry them into their positions in which they do not function, as designed, in controlling the predetermined regular step-by-step movement of the escapement-wheel, resulting in the "racing" of the same and a failure of the clock to keep time.

The object of my present invention is to provide a tower-clock escapement of the character described with means for checking the lifting of the gravity-arms under sudden accessions of power.

With these ends in view, my invention consists in a tower-clock escapement having two pivotal gravity-arms, one of which is provided with a checking-member preventing the said gravity-arms from being lifted beyond the predetermined positions within the limits of which the said gravity-arms control the locking of the escapement wheel.

My invention further consists in a tower-clock escapement having two pivotal gravity-arms respectively provided with co-acting checking-arms preventing the respective gravity-arms from being lifted beyond the predetermined positions within the limits of which the said gravity-arms control the locking of the escapement-wheel.

My invention further consists in certain details of construction and combinations of parts as will be hereinafter described and pointed out in the claims.

In carrying out my invention as herein shown, I employ two corresponding checking-arms 2, 3, each provided at its inner end with an abutment-finger 4, the said fingers being respectively bent in opposite directions so as to form abutments each for the other under emergency conditions. The outer ends of the said checking-arms 2, 3, are respectively fastened by screws 5 or otherwise, to the lower ends of two pivotal gravity-arms 6 the upper ends of which are suspended by pivots 7 from a gravity-plate 8, forming a part of the clock-frame which is not shown. As shown, the escapement-wheel consists of a hub 9 turning upon a shaft 10 and furnished with six escapement-spokes 11, though the number of such spokes is not material to my invention. The said hub 9 is also furnished with three lifting-pins 12 arranged equidistant from each other around the shaft 10 and successively co-acting with lifting-arms 13 extending inward from the gravity-arms 6, the inner ends of the said arms 13 being separated from each other in the vertical plane by a distance determined by the separation of the lifting-pins 12. The outer ends of the escapement-spokes 11 are flattened to form locking-fingers 14 co-acting with pallets 15 respectively secured in corresponding positions to the gravity-arms 6. The lower ends

of the arms 6 are furnished, as usual, with studs 16 co-acting with the opposite faces of the pendulum-rod 17 the upper end of which is furnished with a top-nut 18 slotted 5 as at 19 for the reception of the lower end of the pendulum-spring 20 the upper end of which is adjustably held between chops 21 clamped upon the spring 20 by means of chop-screws 22 mounted in arms 23 depending 10 from what is called the top-girt, which is not shown. From the said arms 23 depend the usual safety-hangers 24 receiving the ends of the pendulum-pin 25 which is passed through the spring 20 and through 15 the top-nut 18 and secures the spring 20 thereto. It will be understood that the hangers 24 are only brought into play in case the spring 20 should break.

Under normal conditions the gravity escapement mechanism herein described, operates in the usual and well known manner, the arms 6 being alternately lifted into their intermediate positions by the pressure of the lifting-pins 12 upon the ends of the lifting-arms 13, and being alternately lifted 20 still higher into their unlocking positions by the pressure of the pendulum-rod itself on the studs 16 in the lower ends of the arms 6. Thus when the pendulum-rod 17 swings 25 from left to right to the limit of its excursion in that direction, it acts through the stud 16 of the right hand arm 6 to lift the same to its highest position and hence to release the escapement-spoke 11 at the time 30 engaged with the pallet 15. The moment the said spoke is released, the power of the power-train will act to turn the escapement wheel 9 through an arc represented by one-sixth of its entire rotary movement during 35 which one of the lifting-pins 12 will co-act with the lifting-arm 13 of the left hand gravity-arm 6 to raise the same into its intermediate position. Now as the pendulum-rod is swung by the gravity action of the 40 right-hand arm 6 to the extreme limit of its excursion to the left, it will engage the stud 16 in the lower end of the left hand gravity-arm 6 and raise the same to the limit of its raised position at which time it will release 45 the escapement-spoke 11 engaged with its pallet 15. The ensuing turning of the escapement-wheel lifts the right hand arm 6 into its intermediate position after which it is raised to the limit of its lifted position by 50 the pendulum-rod swinging to the limit of its excursion to the right and so on.

During the normal operation of the escapement-mechanism the interlocked checking-arms 2, 3, travel with respect to each 55 other without developing any friction or performing any function. If, however, any sudden access of power should be thrown upon the escapement, tending to lift the

pivotal gravity-arms by momentum beyond their highest or locking-positions, the fingers 4 of the checking-arms will be brought into abutment and limit the lifting of the arms 6 within the positions in which their pallets properly co-act with the escapement-spokes of the escapement wheel so that any "racing" of the escapement-wheel is effectively prevented and hence vagaries in the behavior of the clock.

It will be understood from the foregoing that my improved safety appliance only 75 functions in emergencies where there is a sudden access of power, tending to carry the gravity-arms of the escapement beyond their locking positions. Under ordinary circumstances the mechanism acts as though the checking-arms were not present.

In the modified construction shown by Figs. 3 and 4, instead of employing two checking-arms, I employ a single checking-arm 26 secured by screws 27 to the lower 80 end of the right-hand pivotal gravity-arm 28 the corresponding arm 29 of which is furnished with an abutment 30 located in position to co-act with a checking-finger 31 formed by turning the free end of the arm 26 at a right angle. It will be readily understood that the arm 26 will effectually operate to check any undue separation of the arms 28 and 29 beyond the predetermined 85 positions of lifting movement within which they control the escapement of the escapement-wheel.

It is not essential that the checking-arms 2 and 3 or the checking-arm 26 be constructed in the particular manner shown and described, nor that they be applied to the lower ends of the pivotal gravity-arms, my invention comprehending the employment of one or more checking-members however constructed and arranged, so long as they 90 act as checks preventing the gravity-arms from being suddenly lifted into positions in which they do not control the regular locking and releasing of the escapement-wheel.

I claim:—

1. In a tower-clock escapement, the combination with two gravity-arms, a pendulum-rod and an escapement-wheel, of checking means applied to one of the said arms to prevent the arms from being lifted beyond 115 their locking-positions with respect to the escapement-wheel.

2. In a tower-clock escapement, the combination with two gravity-arms, a pendulum-rod and an escapement-wheel, of co-acting checking means applied to the respective arms to prevent the same from being lifted beyond their locking positions with respect to the escapement wheel.

3. In a tower-clock escapement, the combination with two pivotal gravity-arms, a

pendulum-rod and an escapement-wheel, of two checking-arms respectively applied to the gravity-arms and having their inner ends adapted to constitute abutments each for the other to prevent the gravity-arms from being carried by a sudden access of power, beyond their locking positions.

In testimony whereof, I have signed this specification in the presence of two subscribing witnesses.

ARTHUR M. GORDON.
